BALANCED SPRINKLER BEARING

Philippi Gordon, Roscoe, Calif.

Application February 1, 1932, Serial No. 590,044

4 Claims. (Cl. 299—69)

My invention relates to rotary sprinkler heads such as employed for overhead irrigation purposes, and relates particularly to a balanced, water-lubricated thrust bearing construction for the rotary parts of sprinkler heads.

Sprinkler devices for overhead irrigation include essentially a stationary body from which a rotary tube extends upwardly to a nozzle arrangement which generally includes radial pipes having discharge orifices at their outer ends, some means, such as the reaction of the water being discharged, producing rotation of the nozzle or sprinkler parts of the sprinkler device. A fault encountered in the use of rotary sprinklers of this type resides in the rapid cutting away and binding of the thrust bearings, which in customary construction are so placed that foreign substances, such as sand and bits of shell, may enter therein and cause a rapid wearing away of the thrust bearing surfaces.

It is an object of my invention to provide a sprinkler head in which the upward thrust of water passing through the delivery tube and the sprinklers of the rotary part of the sprinkler device is balanced by a fluid pressure exerted in the opposite direction, or downwardly, the thrust bearing structure being so formed that the water flowing to the delivery tube must pass between thrust bearing surfaces so that the thrust is received on a wall of water.

Further objects and advantages of the invention will be made evident throughout the following part of the specification.

Referring to the drawing, which is for illustrative purposes only,

Fig. 1 is an elevational view, to reduced scale, showing a sprinkler device equipped with a preferred form of my invention.

Fig. 2 is an enlarged, vertically sectioned view of the sprinkler head shown in Fig. 1.

Fig. 3 is a cross section on a plane represented by the line 3—3 of Fig. 2.

Fig. 4 is a vertically sectioned view showing an alternative form of thrust bearing construction which may be employed in the practice of my invention.

In Fig. 1 I show a sprinkler device consisting of a rotary element 11 supported by a bearing head 12 mounted on the upper end of a standpipe 13 which connects by means of a T 14 in a line pipe 15. The rotary element 11 includes a pair of radially extending pipes 16 having nozzles 17 formed at the ends thereof, for discharging water tangentially whereby to produce rotation of the rotary element 11.

As shown in Fig. 2, the radial pipes 16 are secured to a rotary delivery tube 18 by means of a T 19. For supporting the tube 18, the bearing head 12 is provided, this bearing head including a casing 21 comprised of a lower or body portion 22 which is threaded onto the upper end of the standpipe 13, and an upper or cap portion 23 which has threaded engagement at 24 with the upper portion of the part 22. The cap 23 provides an opening 25 centralized with respect to a vertical axis A—A and an upwardly extending wall 26 which forms a radial bearing for the rotary tube 18. To prevent escape of water from the interior of the casing 21 through the opening 25, sealing means is provided in the form of a packing space 28 at the upper end of the wall 26 in which packing 29 may be compressed by means of a gland nut 31. To prevent entry of abrasive materials into the bearing provided by the wall 26, and also to prevent escape of water through the opening 25, I employ sealing means 32 below the opening 25, this sealing means 32 being situated in a threaded counterbore 33 in the lower portion of the cap 23, and consisting of an annular radial wall 34 having a cylindrical wall 35 of flexible material, such as leather, extending downwardly around and in engagement with the exterior of the tube 18. The member 35 may be held in place by means of a clamping washer 37 and a threaded clamping ring 38 which is screwed upwardly into the counterbore 33. For lubricating the radial bearing, a grease fitting 40 may be employed in a position to feed grease through an opening 41 to a spiral slot 42 cut in the inner face of the wall 26.

Within the casing 21 is a hollow thrust bearing body 43 comprising a conical wall 44 which converges upwardly to an aperture 45 concentric with the axis A—A, a bottom cap or wall 46 which is threaded onto the lower end of the conical wall 44 in position to close the lower end of the thrust bearing body 43, and a radial wall or flange 47, the periphery of which is held between the cap 23 and the upper lip of the lower body portion 22 of the casing 21. The flange 47 is provided with a plurality of water passages 48.

As further shown in Fig. 2, the lower end of the tube 18 is expanded within the thrust bearing body 43 to form an annular, rotary thrust bearing wall 50 adapted to cooperate with the stationary wall 44. The wall 50 is preferably made conical, as shown, to agree with the conical form of the wall 44.

The operation of the bearing is as follows: Water from a source of supply passes upwardly into

the casing 21, as indicated by the arrow 51, this water then passing through the openings 48 in the flange 47 and then downwardly through the aperture 45 into the space 52 between the conical walls 44 and 50. From the lower end of the wall 50, the water passes upwardly, as indicated by the arrows 53, and at the upper end of the tube 18 the water is diverted laterally, as indicated by the arrows 54, into the radial pipes 16, to be subsequently discharged from the nozzles 17. The upward thrust of the water against the upper wall 55 of the T 19 tends to move the tube 18 upwardly through the aperture 45, the opening 25, and the radial bearing 26. The distance which the tube 18 may be moved upwardly is controlled by the volume of water flowing downwardly through the aperture 45 and the space 52; accordingly, the tube 18 will move upwardly until the conical wall 50 is in such position relative to the conical wall 44 that the upper end of the conical space 52 will be of a cross sectional area capable of permitting a flow of water therethrough equal to the flow of water which is being discharged from the sprinkler device. The upward thrust of the thrust bearing parts formed by the conical members 44 and 50 is received on the wall of water in the space 52; therefore the walls 44 and 50 do not engage, and consequently there is substantially no thrust bearing wear. When the sprinkler device is shut off, the lower end of the conical wall 50 may rest on radial ribs 57 formed in the lower wall or cap 46 of the bearing body 43, but when the water is turned on, it passes through the spaces between the radial ribs 57 and under the lower edge of the wall 50 into the rotary tube 18, after which the upward thrust of the water moves the tube 18 upwardly until the wall 50 is in operating position relative to the wall 44.

In Fig. 2 I have shown a form of my invention in which the stationary and rotary thrust bearing walls 44 and 50 lead or converge toward the aperture 45 in the manner of conical figures. In Fig. 4 I show an alternative form of my invention in which the stationary and rotary thrust bearing walls are substantially radial. In this figure I have duplicated many of the parts shown in Fig. 2; consequently they have been given the same numbers as those employed in Fig. 2 so that the description relative to Fig. 2 will apply thereto. The alternative form of my invention differs from the preferred form in that the stationary thrust bearing body 43 has a radial stationary thrust bearing wall 44a which converges or leads toward the aperture 45, and the lower end of the rotary tube 18 is provided with a radial rotary thrust bearing wall 50a projecting under the wall 44a. In this form of the invention the water which is to be discharged from the sprinkler nozzle 17 must pass through a course indicated by the arrows 60, and consequently must pass through the space 52a between the walls 44a and 50a, thereby controlling the upward movement of the tube 18 in the manner described relative to the walls 44 and 50 of Fig. 2. In the construction of the device it is preferable that the annular area indicated at 61 shall be equal to the interior area of the tube 18.

Although I have herein shown and described my invention in simple and practical form, it is recognized that certain parts or elements thereof are representative of other parts, elements, or mechanisms which may be employed in substantially the same manner to accomplish substantially the same results; therefore, it is to be under-

stood that the invention is not to be limited to the details disclosed herein but is to be accorded the full scope of the following claims.

I claim as my invention:

1. A floating bearing device of the character described, including: a hollow cup-shaped bearing body essentially closed except for a fluid inlet aperture formed in the wall thereof, said wall being constricted toward said aperture; a rotary delivery tube extending outwardly from said hollow bearing body through said aperture, the inner end of said tube being annularly expanded to form a flow throttling means in conjunction with said wall defining said aperture; a fluid distributing member secured to the outer part of said delivery tube; means for positively delivering fluid inwardly through the annular space formed between said tube and said wall defining said aperture into said bearing body and the inner end of said tube; and means for supporting said tube so that it may rotate and so that it may move axially outwardly to such a position that said annularly expanded inner end of said tube and said wall defining said aperture will form a fluid bearing space filled by and controlled in size by the water flowing into said hollow bearing body through said aperture. 80

2. A floating bearing device of the character described, including: a hollow cup-shaped bearing body essentially closed except for a fluid inlet aperture formed in the wall thereof, said wall being constricted toward said aperture; a rotary delivery tube extending outwardly from said hollow bearing body through said aperture, the inner end of said tube being conically expanded to form a flow throttling means in conjunction with said wall defining said aperture; a fluid distributing member secured to the outer part of said delivery tube; means for positively delivering fluid inwardly through the conical space formed between said tube and said wall defining said aperture into said bearing body and the inner end of said tube; and means for supporting said tube so that it may rotate and so that it may move axially outwardly to such a position that said conically expanded inner end of said tube and said wall defining said aperture will form a fluid bearing space filled by and controlled in size by the water flowing into said hollow bearing body through said aperture. 105

3. A floating bearing device of the character described, including: a hollow cup-shaped bearing body essentially closed except for a fluid inlet aperture formed in the wall thereof, said wall being constricted toward said aperture; a rotary delivery tube extending outwardly from said hollow bearing body through said aperture, the inner end of said tube being annularly expanded to form a flow throttling means in conjunction with said wall defining said aperture; a fluid distributing member secured to the outer part of said delivery tube; means comprising walls forming a passage leading externally of said hollow bearing body to said fluid inlet aperture, for positively delivering fluid inwardly through the annular space formed between said tube and said wall defining said aperture into said bearing body and the inner end of said tube; and means for supporting said tube so that it may rotate and so that it may move axially outwardly to such a position that said annularly expanded inner end of said tube and said wall defining said aperture will form a fluid bearing space filled by and controlled in size by the water flowing into said hollow bearing body through said aperture. 120

145 150

4. A floating bearing device of the character described, including: a hollow bearing body having an aperture through which the greatest proportion of the water in filling said body is caused to flow, and a stationary bearing wall constricted toward said aperture; a rotary fluid delivery tube extending from said aperture, said delivery tube having its inner end annularly expanded; means outside said bearing body for delivering fluid to said tube through the annular space in said aperture around said delivery tube; and means for

supporting said delivery tube so that it may rotate and so that it may move outwardly to carry the expanded inner end of said delivery tube toward the constricted portion of said stationary bearing wall of said hollow bearing body to an operating position in which the annular space between said stationary bearing wall and said expanded end of said delivery tube corresponds to the volume of fluid flowing into said hollow bearing body through said aperture.
